MUSICAL HOLDING DEVICE

Rudolf Trevor and Leslie Mende, New York, N. Y.,
assignors to Tre-Mend Novelty Corp., New York,
N. Y., a corporation of New York

Application March 12, 1948, Serial No. 14,604

8 Claims. (Cl. 84—95)

1

Our present invention relates to toothbrush holders.

It is an object of our present invention to combine with a toothbrush holder a musical device, preferably spring operated musical means, in such a manner that these musical means are able to operate only while the toothbrush is removed from the toothbrush holder.

A further object of our present invention is to provide a combined toothbrush holder and musical device of the above type which is adapted to hold two toothbrushes and where the spring operated musical means are able to operate only while both toothbrushes are removed from the toothbrush holder.

With the above objects in view, our present invention mainly consists of a combined toothbrush holder and musical device comprising in combination a casing, spring operated musical means arranged within the casing, a movable member forming part of the spring operated musical means, said member moving during operation of the musical means, but stopping such operation while prevented from moving, and at least one holding means for a toothbrush reaching into the casing, and arranged so that when a toothbrush is inserted into the holding means the toothbrush prevents movement of the movable member, thereby stopping operation of the musical means.

In accordance with a preferred embodiment of our present invention, we provide in a combined holder and musical device of the above type, a blocking member arranged within the casing movably between inoperative position outside of the path of the movable member, and blocking position moved into the path of the movable member preventing moving of the same, and activating means adapted to actuate the blocking member and being in turn operated by a toothbrush in such a manner as to move the blocking member from inoperative into blocking position when the toothbrush is inserted into the holding means.

It is, of course, also possible to provide instead of the above described blocking member and activating means, one single turnable double armed blocking member arranged within the casing turnably between inoperative position in which one lever arm of the double armed blocking member is located within the path of a toothbrush inserted into the holding means and the other lever arm is located outside of the path of the movable member and blocking position in which the one lever arm is moved out of the path of a

2

toothbrush inserted into the holding means and the other lever arm is moved thereby into the path of the movable member preventing movement of the same.

5 The movable member forming part of the spring operated musical means as defined above, is preferably a turnable speed regulating member. However, we wish to note that it is also possible to stop movement of the above defined 10 movable member not only by moving a blocking member into the path of the same, but also by braking its movement, e. g. by pressing the blocking member against the movable member.

We have found that in some cases we might 15 entirely omit provision of a separate blocking member, and instead thereof arrange the holding means for the toothbrush in such a manner that when a toothbrush is inserted into the holding means it reaches the path of turning of the turnable speed regulating member thereby preventing 20 turning of the same and stopping operation of the musical means.

If it is desired to prevent operation of the musical means only while two toothbrushes are held 25 by the holding means, we preferably provide two holding tubes reaching into the holder casing and each adapted to hold one toothbrush, an aperture in the wall of each of the holding tubes, an actuating lever turnably arranged within the casing 30 so as to reach with its free end through the aperture in one of the holding tubes, a blocking lever pivoted to said actuating lever spaced from the pivoting point thereof so as to be adapted to reach through the aperture in the other of the holding tubes in such a manner that the blocking 35 lever is moved into the path of the turnable speed regulating member only when a toothbrush is inserted in each of the holding tubes, turning both the actuating lever and the blocking lever, and spring means tending to turn both the actuating lever and the blocking lever with its free end portions into the holding tubes into the path of the corresponding toothbrush.

The novel features which I consider as characteristic for my invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a rear view of a combined toothbrush holder and musical device according to our present invention;

Fig. 2 is a horizontal section of the combined toothbrush holder and musical device shown in Figure 1, along line 2—2 of Figure 1;

Fig. 3 is a rear view of another combined toothbrush holder and musical device similar to the one shown in Figure 1;

Fig. 4 is a horizontal section of the combined holder and musical device shown in Figure 3 along line 4—4 of Figure 3;

Fig. 5 is a rear view of still another modified combined toothbrush holder and musical device;

Fig. 6 is a horizontal section through the holder shown in Figure 5 along line 6—6 of that figure; and

Fig. 7 is a rear view of the combined holder and musical device shown in Figures 5 and 6 with toothbrush inserted in both holding tubes.

The combined toothbrush holder and musical device shown in Figures 1 and 2, consists of a casing 10, in which the musical movement 11 of a music box of well known type is arranged. As such musical movements are commonly used for other purposes and well known to everybody skilled in this art, we will not describe in detail, but only note that they are spring driven and include a turnable speed regulating member 12 driven by the spring. It is evident that if and when this speed regulating member 12 is prevented from turning, the movement is stopped and no music is reproduced.

We provide also within the casing 10 a tubular toothbrush holding member 13, provided with an aperture 14 which is arranged so that the wings 15 of the speed regulating member 12 reach, during turning through this aperture 14, into the tubular holding member 13.

It is evident that if a toothbrush 16 indicated in dotted lines, is inserted into the tube 13, it will be located in the path of the wings 15 of the speed regulating member 12, and thus prevent turning of the same.

The moment the toothbrush is removed the speed regulating member 12 is free to turn, and music is reproduced.

In the embodiment shown in Figures 3 and 4, the toothbrush does not reach directly into the path of the speed regulating member 12, but we provide a double armed blocking lever 17 pivoted at 18 to the base plate 19 of the musical movement 11. This double armed blocking lever is arranged so as to reach with its one lever arm through the aperture 14 into the holding tube 13. The other lever arm 21 of the double armed blocking lever 17 is turnable from the inoperative position shown in Figure 3 into blocking position indicated in dotted lines located in the path of the speed regulating member 12.

A small spring 22 is provided so as to permanently tend to turn the blocking lever 17 in direction of arrow 23.

It should be noted that the blocking lever 17 is arranged so that in the inoperative position shown in full lines it does not block turning of the speed regulating member 12, while if the toothbrush 16 is inserted it turns the blocking lever 17 against direction of arrow 23 into the blocking position shown in dotted lines: in this position the blocking lever prevents turning of the speed regulating member 12, stopping operation of the musical movement. The moment the toothbrush is again removed from the holding tube 13, the blocking lever is automatically turned by means of spring 22 in direction of arrow 23 into the inoperative position shown in Figure 3 in full lines permitting rotation of the

speed regulating member 12, and operation of the music movement.

In the embodiment shown in Figures 5 to 7, we provide an arrangement which blocks operation of the music movement 11 only if both toothbrushes 24 and 25 are inserted into the corresponding holding tubes 26 and 27.

In order to enable this to be done, we provide a lever system consisting of the actuating lever 28 pivoted at 29 to the housing 30 and reaching with its free end portion 31 through the aperture 32 into the holding tube 26. We further provide the blocking lever 33 pivoted at 34 to the actuating lever 28, and reaching with its free end portion 35 through the aperture 36 into the holding tube 29.

Spring 37 permanently tends to turn the actuating lever 28 in direction of arrow 38, while spring 39 secured at its both ends to the levers 28 and 33 permanently tends to turn the blocking lever 33 about its pivoting point 34 in direction of arrow 40. Excessive turning of the levers 28 and 33 is prevented by the upper edges 41 and 42 of the apertures 32 and 36, respectively.

In Figure 5 we have shown our holder in non-blocking position permitting operation of the musical movement.

If one toothbrush only is inserted in one of the holding tubes 26 and 29, this will not result in blocking of turning of the speed regulating member 12: namely, if only the toothbrush 25 is inserted into the holding tube 29, this will result only in turning of the blocking lever 33 about the pivot 34, which alone will not turn this lever into the path of the speed regulating member 12. Similarly, if only the toothbrush 24 is inserted into the corresponding holding tube 26, this will only result in turning of the actuating lever 28 about pivot 29 while the blocking lever 33 will be held out of the path of turning of the speed regulating member 12 by the spring 39, permanently turning it in direction of arrow 40.

Only if both toothbrushes 24 and 25 are inserted into the holding tubes, will both levers be turned into the position shown in Figure 7, resulting in movement of the blocking lever 33 into the path of the speed regulating member 12, preventing turning of the same and stopping operation of the musical movement.

We wish to note that in order to enable free movement of the blocking lever 33 if only the toothbrush 24 is inserted, we provide in the wall of the holding tube 29 an additional aperture 43, enabling free movement of this lever in direction of arrow 44.

We wish also to stress that the term "toothbrush" as used above and in the following claims is intended to be interpreted broadly, i. e. to define every possible type of elongated, preferably rod-shaped member.

It will be understood that each of the elements described above, or two or more together, may also find a useful application in other types of combined holding and musical devices differing from the types described above.

While I have illustrated and described the invention as embodied in combined toothbrush holders and musical devices, I do not intend to be limited to the details shown, since various modification and structural changes may be made without departing in any way from the spirit of my invention.

Without further analysis, the foregoing will so fully reveal the gist of my invention that others can by applying current knowledge readily adapt

it for various applications without omitting features that, from the standpoint of prior art, fairly constitute essential characteristics of the generic or specific aspects of this invention, and therefore, such adaptations should and are intended to be comprehended within the meaning and range of equivalence of the following claims.

What we claim as new and desire to secure by Letters Patent is:

1. A combined toothbrush holder and musical device comprising in combination a casing having a casing wall; spring operated musical means arranged within said casing; a movable member forming part of said spring operated musical means, said member moving during operation of said musical means but stopping such operation while prevented from moving; an aperture in said casing wall; at least one holding means for a toothbrush arranged within said casing under said aperture; and a turnable double armed blocking member arranged within said casing turnably between inoperative position in which one lever arm of said double armed blocking member reaches into said holding means and the other lever arm is located outside of the path of said movable member and blocking position in which said one lever arm is moved out of said holding means and the said other lever arm is moved thereby into the path of said movable member preventing movement of the same.

2. A combined toothbrush holder and musical device comprising in combination a casing having a casing wall; spring operated musical means arranged within said casing; a turnable speed regulating member forming part of said spring operated musical means, said member moving during operation of said musical means, but stopping such operation while prevented from moving; an aperture in said casing wall; holding means for a toothbrush arranged within said casing under said aperture; and a turnable double armed blocking member arranged within said casing turnably between inoperative position in which one lever arm of said double armed blocking member reaches into said holding means and the other lever arm is located outside of the path of said movable member and blocking position in which said one lever arm is moved out of said holding means and the said other lever arm is moved thereby into the path of said turnable speed regulating member preventing movement of the same.

3. A combined toothbrush holder and musical device comprising in combination a casing having a casing wall; spring operated musical means arranged within said casing; a turnable member forming part of said spring operated musical means, said turnable member turning during operation of said musical means but stopping such operation when prevented from turning; an aperture in said casing wall; a holding tube for a toothbrush arranged within said casing under said aperture; an aperture in the wall of said holding tube within said casing; and a movable blocking member arranged within said casing movably between inoperative position reaching through said aperture into said holding tube but being located outside of the path of turning of said turnable member and blocking position moved by a toothbrush inserted into said holding tube outside of said tube and into the path of turning of said turnable member, thereby preventing turning of the same and stopping operation of said musical means.

4. A combined toothbrush holder and musical

device comprising in combination a casing having a casing wall; spring operated musical means arranged within said casing; a turnable speed regulating member forming part of said spring operated musical means, said turnable speed regulating member turning during operation of said musical means but stopping such operation when prevented from turning; an aperture in said casing wall; a holding tube for a toothbrush arranged within said casing under said aperture; an aperture in the wall of said holding tube within said casing; and a double armed blocking lever arranged within said casing turnably between inoperative position reaching with one lever arm through said aperture in said holding tube into the path of a toothbrush inserted in said holding tube, but being located with its other lever arm outside of the path of turning of said turnable speed regulating member and blocking position in which said one lever arm is turned by a toothbrush inserted in said holding tube outside of the path of the same within said holding tube and said other lever arm is turned thereby into the path of turning of said turnable speed regulating member, preventing turning of the same and stopping operation of said musical means.

5. A musical toothbrush holder comprising in combination a casing having a casing wall; spring operated musical means arranged within said casing; a movable member forming part of said spring operated musical means, said member moving during operation of said musical means but stopping such operation while prevented from moving; two apertures in said casing wall; two holding means, each arranged within said casing under one of said apertures and adapted to hold one toothbrush; and blocking means arranged within said casing movably between inoperative position outside of the path of said movable member and operative blocking position moved into the path of said movable member preventing movement of the same, said blocking means constructed and arranged so as to be moved by both said toothbrushes from inoperative into operative blocking position by insertion of both said toothbrushes through the corresponding apertures into the corresponding holding means.

6. A musical toothbrush holder comprising in combination a casing having a casing wall; spring operated musical means arranged within said casing; a movable member forming part of said spring operated musical means, said member moving during operation of said musical means but stopping such operation while prevented from moving; two apertures in said casing wall; two holding means, each arranged within said casing under one of said apertures and adapted to hold one toothbrush; blocking means arranged within said casing movably between inoperative position outside of the path of said movable member and operative blocking position moved into the path of said movable member preventing movement of the same, said blocking means constructed and arranged so as to be moved by both said toothbrushes from inoperative into operative blocking position by insertion of both said toothbrushes through the corresponding apertures into the corresponding holding means; and spring means permanently tending to move said blocking means from operative into inoperative position.

7. A musical toothbrush holder comprising in combination a casing having a casing wall; spring operated musical means arranged within

said casing; a movable member forming part of said spring operated musical means, said member moving during operation of said musical means but stopping such operation while prevented from moving; two apertures in said casing wall; two holding means, each arranged within said casing under one of said apertures and adapted to hold one toothbrush; and blocking means arranged within said casing tending to be permanently located in inoperative position outside of the path of said movable member and movable from such inoperative position into operative blocking position located in the path of said movable member preventing movement of the same, said blocking means constructed and arranged so as to be moved by both said toothbrushes from inoperative into operative blocking position by insertion of both said toothbrushes through the corresponding apertures into the corresponding holding means.

8. A musical toothbrush holder comprising in combination a casing having a casing wall; spring operated musical means arranged within said casing; a movable member forming part of said spring operated musical means, said member moving during operation of said musical means but stopping such operation while prevented from moving; two apertures in said casing wall; two holding means, each arranged within said casing under one of said apertures and adapted to hold one toothbrush; and blocking means arranged within said casing movably between inoperative

position outside of the path of said movable member and operative blocking position moved into the path of said movable member preventing movement of the same, said blocking means constructed and arranged so as to project in inoperative position into both said holding means for said toothbrushes so as to be moved by said toothbrushes from inoperative into operative position when both said toothbrushes are inserted through the corresponding apertures into the corresponding holding means.
